(57) **CLAIM**

The ornamental design for a grip for digital camera, as shown and described.

DESCRIPTION

FIG. 1 is a front perspective view of a grip for digital camera showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is an enlarged view of the encircled portion as shown in FIG. 1;

FIG. 9 is an enlarged view of the encircled portion as shown in FIG. 2;

FIG. 10 is an enlarged view of the encircled portion as shown in FIG. 3; and,

FIG. 11 is an enlarged view of the encircled portion as shown in FIG. 7.

The broken lines illustrating portions of the grip for digital camera are for environmental purposes only and form no part of the claimed design.

The dot-dash broken lines encircling portions of the claimed design that are illustrated in enlargements form no part of the claimed design.
